UNITED STATES PATENT OFFICE.

JUDSON M. GRIFFIN, OF DETROIT, MICHIGAN.

ABRADING-SHOE.

SPECIFICATION forming part of Letters Patent No. 738,029, dated September 1, 1903.

Application filed January 15, 1903. Serial No. 139,102. (No model.)

To all whom it may concern:

Be it known that I, JUDSON M. GRIFFIN, a citizen of the United States, residing at Detroit, county of Wayne, State of Michigan, have invented a certain new and useful Improvement in Abrading-Shoes; and I declare the following to be a full, clear, and exact description of the same, such as will enable others skilled in the art to which it pertains to make and use the same, reference being had to the accompanying drawings, which form a part of this specification.

This invention relates to abrading-shoes for truing up car-wheels, and has for its object an improved form of abrading-shoe adapted to be used for the specified purpose.

In the drawings, Figure 1 is a perspective of a shoe embodying the invention. Fig. 2 is a cross-section at the line $x x$ of Fig. 1. Fig. 3 is a perspective of a shoe embodying the same invention, but arranged to be used for grinding the wheel at a different place from the place ground when the shoe shown in Fig. 1 is used.

Car-wheels when in use become worn in spots or in lines, and in truing them up with an abrading-shoe it is desirable that the shoe be so constructed that at all times it will engage closely across the entire edge surface of

the wheel; but if the shoe be made with an abrading-surface of uniform hardness it grinds and cuts away some parts that should not be ground and cut away. To prevent this, I make the abrading-shoe of a case of

metal of proper shape and fill into the case of metal abrading-blocks which are made hard and are adapted to cut in those places which will contact the parts of the wheel that are to be cut away and make it soft and fri-

able in those parts of the shoe which are to contact the portions of the wheel that are not to be cut away, yet the soft and friable parts are made sufficiently hard to retain their shape and act as a support or rest against the

surface of the wheel, so that all parts of the abrading-block, both those which are cutting and those which are not cutting, are in contact with the wheel under treatment and are

acting as a frictional brake—for example, in the form shown in Fig. 1, which is intended to be used to grind the flange of a wheel. The case A is provided with a number of pockets 1, 2, and 3, all filled with abrading material that is hard and cutting at the part 4, which engages the flange of the wheel, and the part 5 is filled with softer and more friable or non-abrasive material, which while supporting the abrasive blocks will serve as an ordinary friction-brake and furnish a support for the shoe against the tread of the wheel.

In the form shown in Fig. 3 the case B is divided into pockets 7, 8, and 9, which are filled with abrading material with the side sections 10, 10^a, 11, 11^a of hard durable cutting material and between the hard sections is interposed a section 12 12^a of softer and more friable material or a non-abrasive material. A shoe thus formed is intended to cut the tread of a wheel that has been worn along the middle line thereof, in which case it is desirable to cut away the two sides of the tread, leaving the middle line, the most worn part of the tread, without cutting it to any extent.

What I claim is—

1. In an abrading-shoe for truing car-wheels, the combination of a case adapted to hold abrading-blocks, a block made in sections of hard grinding material and non-abrasive material, substantially as described.

2. In an abrading-shoe for truing car-wheels, a block having one part thereof made abrasive, and one part thereof made non-abrasive for the purpose specified.

3. In an abrading-shoe for truing car-wheels, a block having separate portions of unequally-abrading quality, substantially as described.

In testimony whereof I sign this specification in the presence of two witnesses.

JUDSON M. GRIFFIN.
